UNITED STATES PATENT OFFICE

145,051

DESIGN FOR A COMBINATION HAND MIRROR AND STAND OR SIMILAR ARTICLE

Charles David Blake, Pelham Manor, N. Y., assignor to Premier Optical Products, Inc., New York, N. Y.

Application September 10, 1945, Serial No. 121,990

Term of patent 7 years

(Cl. D86—10)

To all whom it may concern:

Be it known that I, Charles David Blake, a citizen of the United States of America, residing at Pelham Manor, Westchester county, State of New York, have invented a new, original, and ornamental Design for a Combination Hand Mirror and Stand or Similar Article, of which the following is a specification, reference being had to the accompanying drawing, forming a part thereof.

The figure is a perspective view of a combination hand mirror and stand or similar article.

I claim:

The ornamental design for a combination hand mirror and stand or similar article, as shown

CHARLES DAVID BLAKE.
